CURTAIN ROD

Pierre F. Dover, Rye, N. Y., assignor to H. L. Judd
Company, Inc., New York, N. Y., a corporation
of Delaware

Application May 20, 1938, Serial No 209,003

2 Claims. (Cl. 156—19)

This invention relates to certain new and useful improvements in telescopic curtain rods.

The object is to provide a construction that will permit the rod to be slipped through the rod pocket of a curtain with ease and without danger of injury thereto. This danger is more conspicuous in the case of rods of the so-called "flat" type in which both rod sections may be said to be C-shaped in cross-section with spaced rear flanges forming an open back. Heretofore it not infrequently happened that curtains were injured by catching on burred edges or abrupt shoulders at the rod end upon which the curtain was being threaded or applied. My invention is of particular importance when employed in such a rod since it not only facilitates and shortens the operation of mounting the curtain on the rod, but it obviates the aforesaid danger of injury.

In the drawing—

Fig. 1 is a front elevation of portions of two telescopic rod sections of the so-called "flat" rod type, the outer section being partly broken away;

Fig. 2 is a perspective view on the rear side of the inner rod section shown in Fig. 1;

Fig. 3 is a rear view of the end of a rod showing a modification;

Fig. 4 is a section on the line 4—4 of Fig. 3.

Curtain rods of the so-called "flat rod" type are C-shaped in cross-section and much difficulty is encountered in assembling curtains thereon since the rear flanges, particularly at the threading end of the rod, are commonly rough or burred and tend to catch the threads of the curtain, to their injury. This also frequently renders the operation tedious and slow. To overcome this, I purpose to provide what I will term a guard and guide piece or threading nose at the telescopic end of the rod for facilitating the threading of the rod through curtain hems. This nose, presenting a smooth surface and rounded end, will greatly assist the speed of assembly of the telescopic rod sections and also eliminate the danger of injury to the curtain or curtains. In the drawing I have shown two forms of such a threading nose.

In Figs. 1 and 2, 1 represents the outer rod section and 2 the inner rod section which telescopes with the section 1. When a curtain is threaded it is common practice and most expedient to separate the two rod sections and slide the curtains onto the end of one of said sections, after which the rod sections are assembled and the curtains are adjusted to the proper position on both sections, the same sliding freely from one section onto the other. In these figures I have shown the

rear flanges of the inner rod section at its telescopic end as tapered inwardly toward each other so as to form a contracted end or tip of less diameter than the internal diameter of the outer rod, as indicated in the drawing. 3 is the nose at 5 the tip end of the rod section, the same being preferably an integral portion of the metal of the face of the rod, which portion is bent back so as to properly guard the rough edges of the said flanges and prevent them from catching the 10 threads of a curtain being slipped onto the rod. In this case, the end being tapered it may be easily entered in the curtain pocket or hem and the nose 3 being rounded may be quickly and safely passed through the rod pocket in the curtain as the latter is being drawn onto said rod. Furthermore, by thus forming the telescopic end of the inside rod section 2 the same is easily insertable into the outside section 1 after the curtain has been 15 slid into place on the former.

In Figs. 3 and 4 I have shown a slight modification in which instead of contracting the end of the inner rod by rolling in the rear flanges, said side flanges are cut off on a bevel as indicated at 20 5—5 so as to effect a slight taper. The tip end 25 of this rod section is provided with a nose 6 integral with the face of the rod and turned back to form a smooth-faced incline which may be pushed easily through the curtain rod pocket, 30 since the edges of said nose are positioned sufficiently close to the beveled edges of the flanges to guide the fabric of the curtain freely over the same as the curtain is drawn into place. When it is desired to remove the curtain from the rod, 35 the rod and curtain are detached from the wall 35 and the curtain or curtains may be easily slid off the end of the rod remote from the guard nose, thereby avoiding any danger of catching the curtain on the rear edge of said nose should the same project to any degree above the rear surface of 40 the rod section on which the nose is formed.

I claim:

1. A sheet metal flat curtain rod comprising an inner and an outer rod section, each section having a substantially flat front face and spaced 45 off inwardly directed reinforcing flanges at the rear face, the inner section being telescopically slidable within the outer section, the flanges at the telescopic end of the inner section being cut away from the substantially flat front face adjacent the front end so as to leave an unreinforced bendable tip at the end of the front face, said tip being bent back to form a rounded nose to provide a threading end.

2. In a sheet metal flat curtain rod, two tele- 55

scopic rod sections each having a substantially flat front face with inturned spaced off reinforcing rear flanges, the telescopic end of the inner rod section having spaced apart generally longitudinally extending slits in the front face leaving an unreinforced tongue at the end between said slits, the unreinforced tongue of metal between said slits being bent back to form a smooth

rounded nose, the front ends of said flanges being bent inwardly so as to cause the sides of the rod to converge toward the end, the ends of said flanges and the rounded nose coacting with each other to form a tapered and rounded threading 5
